UNITED STATES PATENT OFFICE.

WILLIAM S. GRAHAM, OF CANTON, ILLINOIS, ASSIGNOR TO PARLIN & ORENDOFF COMPANY, OF CANTON, ILLINOIS, A CORPORATION OF ILLINOIS.

LOCK-LEVER.

SPECIFICATION forming part of Letters Patent No. 778,185, dated December 20, 1904.

Application filed February 18, 1904. Serial No. 194,264.

To all whom it may concern:

Be it known that I, WILLIAM S. GRAHAM, of the city of Canton, county of Fulton, and State of Illinois, have invented certain new 5 and useful Improvements in Lock-Levers, of which the following is a specification.

This invention is particularly applicable to two-row lister-cultivators on which the driver rides between the widely-separated cultivating-frames, and it enables the driver to lift 10 and control the cultivating appliances from his seat.

The cultivating appliances of a lister-cultivator are usually extended to the rear of the 15 lift-levers, and consequently they are raised by a forward pull. The cultivating-frames are two rows apart, or about seven feet between centers, and this throws the lift-hitches out of reach of the driver. A forward thrust 20 on the lift-hitches is an inconvenient movement for the driver to make, the natural and effective movement being a backward pull, and if lift-levers fulcrumed on horizontal pivots are turned toward the driver with sufficient obliquity to bring them within operative 25 reach the lifting force will be applied indirectly or torsionally, with a tendency to twist the lever and cramp the fulcrum.

This invention provides an oblique lever 30 fulcrumed on a pivot at right angles to its length and adapted to develop a forward lift by a backward pull. It also gets the lift end of the lever sufficiently high to connect properly with the cultivating appliances.

The invention is not of necessity confined 35 to lister-cultivators, as there may be other environments in which it would have utility. It is exemplified in the structure hereinafter described, and it is defined in the appended 40 claims.

In the drawings forming part of this specification, Figure 1 is a side elevation of the lever, showing the bearings in section. Figs. 2 and 3 are elevations in a plane at right

angles with the plane of Fig. 1. In Fig. 2 45 the lever is shown in an intermediate position, and in Fig. 3 it is shown in an extreme position.

A bracket 1 provides a horizontal fulcrum 4 for the lift-arm 8. It provides an oblique 50 fulcrum 2 for the lever 6, and it has a sector-formed rack 3 concentric with fulcrum 2. The lift-arm 8 extends upward from its fulcrum in the bracket. Its swinging end 10 is adapted to engage a lift-rod, and it has a segment 55 of a gear-wheel 9 formed on its inner face between its ends and concentric with its fulcrum. The lever 6 has a lock-bolt 11, which engages the notches of rack 3, and its power end is toothed, as shown at 7, to engage the 60 teeth 9 of arm 8. Lugs 5 on bracket 1 provide means for securing the bracket to the cultivator-frame. The lever 6 is of the first class as levers are usually classified, and arm 8 is a lever of the third class. 65

I claim—

1. In a compound lever the combination of a lift-arm having a segment of bevel-gear between its fulcrum and its lift end, a lock-lever fulcrumed obliquely with reference to 70 the lift-arm, and a segment of bevel-gear on the work end of the lock-lever in mesh with the gear of the lift-arm.

2. In a compound lever, the combination of a bracket having two lever-fulcrums and 75 a rack-sector, the fulcrums being non-parallel, a lift-arm pivoted on one of the fulcrums and extended toward the other fulcrum, a segment of gear on the lift-arm, a lock-lever pivoted on the other fulcrum, and a segment 80 of gear on the work end of the lock-lever in mesh with the gear of the lift-arm.

In testimony whereof I sign my name in the presence of two subscribing witnesses.

WM. S. GRAHAM.
